UNITED STATES PATENT OFFICE.

JEFFERSON P. EDWARDS, OF AKRON, OHIO.

IDENTIFICATION CERTIFICATE.

Application filed October 26, 1923. Serial No. 670,861.

To all whom it may concern:

Be it known that I, JEFFERSON P. EDWARDS, a citizen of the United States, residing at Akron, in the county of Summit and State of Ohio, have invented new and useful Improvements in Identification Certificates, of which the following is a specification.

This invention relates to identification certificates and has particular relation to a new and improved finger print certificate adapted for use as a means of identification.

The particular object of the invention is to provide a convenient means for positively establishing personal identification.

A further object is to provide a finger print certificate having a new and improved arrangement of panels or spaces for the signature and finger prints of the person to be identified and having spaces wherein may be designated a validator or validating organization and having spaces or panels for the validator's finger print or signature.

Another object is to provide an identification certificate of the class above indicated which is adapted to be used in combination with a validating certificate which validating certificate is adapted to carry the finger print and signature of a validator, the identification certificate carrying the same validating print as is shown on the validating certificate.

The above objects are accomplished and additional ends are attained by the new and improved certificate herein described and by the arrangement and location of spaces and combinations herein described and illustrated in the accompanying drawing wherein I have shown practical means for carrying the invention into effect, it being understood that the invention is capable of various adaptations and that changes and modifications may be made which come within the scope of the claim hereunto appended.

In the drawings reference characters are employed to designate parts, spaces and locations, as the same are referred to.

Figure 1 is a plan view showing the face of an identification certificate constructed in accordance with this invention.

Figure 2 is a plan view showing the face of a validating certificate adapted to be used in connection with the identification certificate.

My invention may be best described by illustrating its use by a validating organi-

zation to which a person desiring identification would apply for an identification certificate; the identifying organization after thoroughly convincing itself of the persons identity would issue to the person an identification certificate which would bear the name of the validating organization, the signature and finger print of the person connected with the validating organization and herein referred to as the validator and the signature and finger print of the person to be identified. The validating organization would also issue numerous validating certificates, each bearing the validator's finger print and signature. The validating certificates would be made up in large numbers and would be issued to banks, hotels or other organizations to which the person may desire to prove his identity.

A person possessing one of the identification certificates could present it at any bank, or other organization possessing a validating certificate, whereupon the validator's finger print and signature on the identification certificate could be readily compared with the finger print and signature on the validating certificate and it would only be necessary to produce a finger print of the person desiring identification and compare the same with the print on the identification certificate to positively establish the bearers identity. The validating certificate illustrated in Figure 2 is provided with a space 1 for the name of the validating organization and is provided in the upper right hand corner thereof with a space or panel 2 for characters designating the validator or the series and number of the validating print. The lower left hand corner is provided with a space or panel 3 for the validating print and a space 4 is provided for the validator's signature.

The identification certificate is similarly provided with a space 5 for the name of the validating organization and is likewise provided on the upper right hand corner with a space or panel 6 for characters or marks indicating the validator or the number or index number of the validating print and may also be used for the number of the identification certificate. The identification card is also provided in the upper left hand corner with space or panel 9 which is adapted to receive the finger print of the person desiring identification and is provided with the line or space 8 for the signature of the

person desiring identification. The identification certificate is further provided on the lower left hand corner with the space or panel 7 which is adapted to receive the finger print of the validator and is provided with the space or line 10 for the signature of the validator.

It will thus be seen that when the identification certificate is placed in an overlapping position on the validating certificate the panel 7 will be directly to one side of the panel 3 and that the validating print in these panels may be quickly and conveniently compared. The identification certificate may also be provided with the space or panel 11 for characters representing the particular finger from which the identifying print has been produced, such as the characters RI, meaning right index, shown in the panel 11.

To illustrate the use to which my improved invention may be put, I have shown a practical adaptation thereof and have shown finger prints and signatures thereon. The name of the validator 12 has been inserted in the space 5 on the identification card and in the space 1 on the validating card. The validator's signature 13 has been written on the space 4 and the validator's finger print 14 has been impressed in the panel 3. Inasmuch as it would, in most cases, be necessary for a validating company to have a number of validators, a letter, number or other character is used to designate the validator. In the drawing the letter (a) has been inserted in the space 2, to designate the person acting as validator for the validating company.

In preparing an identification card, the person to be identified places his signature 15 on the line 8 and his finger print 16 on the panel 9. The validator then places his finger print 14 in the panel 7 and his signature 13 on the line 10. The validating index character (a) is then placed in the panel 6 and the number of the identification card 250 is also placed in the panel 6. The validating cards are distributed to certain designated organization, such as hotels and banks throughout the world. When a person bearing one of the cards shown in Figure 1 presents it to any of these designated organizations, the character (a) in

the panel 6 is first noted, whereupon the validating card, bearing the character (a) 55 is located, the signature 13 and the finger print 14 on the identification card are then compared with the signature 13 and the finger print 14 on the validating card, to prove the validity of the identification card. 60 The bearer's signature 8 and finger print 9 are then taken and compared with the signature 8 and print 9 on the identification card, thus positively establishing the identity of the bearer. 65

While I have illustrated and described my invention as applied to an identification certificate, it may be applied to various ways and to other certificates and documents of any kind wherein it is necessary or desirable 70 to establish personal identity, and the invention is not confined to the exact form and arrangement herein shown.

What I claim as new and desire to secure by Letters Patent is:— 75

In a card system of identification, in combination, a validating certificate provided with indicia designating the validating organization by which one or more of said certificates are issued to one or more depositories thereof, and also bearing only a validator's signature and finger print to establish authentic origin of the certificate and no identification of the bearer, the said finger print disposed in a panel occupying 80 a portion of one end of the certificate, and an identification bearer's certificate provided with indicia corresponding with that of the validating certificate including the validator's signature and finger print for comparison with those on the validating certificate, and also having thereon the bearer's signature and finger print to be compared 85 with those of the bearer to be submitted on demand, the validator's finger print of the identification certificate being located in a panel also occupying a portion of one end of said certificate in a position corresponding to that of the validator's finger print upon the validating certificate so that when 90 100 the two aforesaid panels will be close together.

In testimony whereof I have hereunto set my hand.

JEFFERSON P. EDWARDS.
